UNITED STATES PATENT OFFICE.

JOHN DARBY, OF SUMMIT, NEW JERSEY, ASSIGNOR TO FRANCIS B. GRIFFIN AND
EDWARD C. WALLACE, BOTH OF NEW YORK, N. Y.

MOVING-PICTURE MACHINE.

1,280,676.

Specification of Letters Patent.

Patented Oct. 8, 1918.

Application filed January 26, 1914. Serial No. 814,427.

To all whom it may concern:

Be it known that I, JOHN DARBY, a citizen of the United States, residing at Summit, in the county of Union and State of New Jersey, have invented certain new and useful Improvements in Moving-Picture Machines, of which the following is a specification.

The invention relates to moving picture projecting machines and more particularly to devices in such machines for the handling of the film strip and to devices and instrumentalities coöperating therewith. Objects of the invention are to provide novel means for quickly arranging the film strip in the machine and with respect to the various parts thereof; to provide for accurately and rapidly establishing a reserve loop of the proper length between the continuously unwinding or supplying means and the intermittent feed past the lens or projecting tube; to provide similarly for such a reserve loop between such intermittent feed and a continuously running rewinding device; to provide novel and efficient mechanism and instrumentalities for effectuating these objects either directly or through coöperation with other mechanisms and parts. These and other objects of invention will in part be obvious and in part will be set forth hereinafter.

The invention consists in the novel parts, constructions, arrangements, combinations and improvements herein shown and described.

The accompanying drawings, referred to herein and forming a part hereof, illustrate one embodiment of the invention, and taken in connection with the description serve to illustrate the principles thereof.

Of the drawings:—

Figure 1 is a side elevation of a machine constructed in accordance with the principles of the invention and showing the mechanisms in the position in which a strip or film is threaded through the machine;

Fig. 2 is the same as Fig. 1, but showing the mechanisms in the position in which they are when the film is being run through the machine;

Fig. 3 is an end elevation looking at Figs. 1 and 2 from the left with the film strip omitted;

Fig. 4 is a section on the line A—B of Fig. 1 on an enlarged scale; 55

Fig. 5 is a fragmentary elevation looking at Fig. 4 from the bottom; and

Fig. 6 is a section through the strip conducting slot at the back of the lens tube on the line C—D of Fig. 3. 60

Referring to the accompanying drawings, illustrating one embodiment of the invention, a frame for the machine is provided comprising a foot or base 1 and a plate 2 extending upwardly therefrom, upon which plate the various mechanisms are mounted and arranged. Carried in a suitable manner upon said frame is a tube 3 carrying the projecting lenses, and attached at its rear end to a plate 4 extending outwardly from the frame 2. Within the tube 3 in proper arrangement and position are the projecting lenses. In front of the lens tube 3 is a rotary shutter 5, carried upon a shaft 6, which shaft 6, through proper connections is rotated in proper time relation with the film strip feeding devices. 70

In accordance with certain features of the invention, the film strip is supplied from a continuously unwinding roll and is rewound upon a continuously winding roll, while the film strip is given a step by step or intermittent feed past the opening in the rear of the lens tube 3, in coöperation with devices for establishing and preserving a reserve loop of just the proper length or extent between the supplying means and the intermittent feed and between the intermittent feed and the rewinding means. 80

In the embodied form, the film strip *a* is wound in a roll upon a reel 7, which reel 7 is rotatable upon a support 8. A pivoted locking latch 9 may be swung into position to permit the sliding of the reel 7 onto the shaft 8 and then said latch may be turned 95 downwardly into the locking position shown in the drawing. A coiled spring 10 working between a pin 11 and a washer 12 serves to permit the sliding of the reel 7 onto the shaft 8, and also serves as a drag or brake 100 upon the reel. The shaft 8 is suitably supported as by an upright rod 13 vertically adjustable in the frame 2, and secured in any position by thumb screw 13'.

The film strip *a* is drawn from the reel 7 105 by the continuously operating unwinding

mechanism comprising a continuously driven sprocket roller 14 carried upon a shaft 15. Said shaft 15 has a pinion 16 in mesh with the gear wheel 17. Said gear wheel 17 is fixed on a shaft 18, which shaft 18 is provided with a driving crank 19. The film strip α passes preliminarily around a guiding roller 20 to properly direct it so that the sprocket teeth of the roller 14 will engage 10 with the sprocket holes in the side edges of the film strip α in a well-known manner.

Mounted upon the frame by suitable pivoted mountings 22 is an arm 21. At or near its other end, the arm 21 carries a roller 15 23. Integral with or fixed to move with the arm 21 is a short arm 24, carrying a roller 25. Fixed to the arm 21 is a two-faced block or cam 26, and coöperating therewith a flat leaf-spring 27. 20 When the film strip α is threaded through the machine, the arm 21 is in the position shown in Fig. 1 and is firmly held in such position by the leaf-spring 27. The film strip α is threaded about the roller 20 over 25 the sprocket teeth of the roller 14, around the roller 25, around the roller 23, and down past the back of the lens tube 3 and on through the machine as will be later described.

30 Before the machine is started, the arm 21 is pressed downwardly to the position shown in Fig. 2, the spring 27 snapping over onto the other face of the block 26, serving thus to firmly hold the arm in this new position.

35 The roller 25 now coöperates with the sprocket roller 14, and preferably has grooved bearing faces at each end thereof, which press against the film strip on each side of the sprocket teeth of the roller 14.

40 The roller 23 at the same time passes into operative relation with a guide plate 29, (which guide plate is located just above the guide for the film strip past the projecting lens tube) and the film strip is thereby 45 guided as it passes downwardly therebetween. An adjustable stop, such as the screw 30 threaded into the machine frame, serves to limit the movement of the arm 21 and to adjust or regulate the position of the

50 rollers 23 and 25. Thus the preliminary reserve loop, that is the one between the reel 7 and the intermittent feeding mechanism is quickly and accurately established of precisely the desired and predetermined length 55 by means of the arm 21, roll 23 and the co-operating devices as just described.

In the embodied form of means for guiding the film strip past the rear end of the lens tube 3, the plate 4 is provided with an 60 aperture 31 of proper size to frame the pictures on the film strip. Carried on the frame 4 is a bracket 32 to which is hinged a door 33, the frame and door forming a guide way for the film strip. The door 33 65 may be provided with a suitable latch 34.

In the door 33 is likewise provided an aperture 35 through which the light is projected from behind. Mounted in suitable bosses 38 in the door 33 are bent flat springs 36 having bearing faces 37 which act as tension devices to hold the film strip flat and smooth against the face of the frame-piece 4. 70

The intermittent film strip feeding means, as embodied, comprises a sprocket roll 40 having series of sprocket teeth 41 and 42 75 adapted to pass through the sprocket holes in the side edges of the film strip. Fast on the shaft 43 of the sprocket roll is a four-pointed star wheel 44 constituting part of a Geneva movement. In mesh with the slots 80 in the star wheel 44 is a pin 45 carried by a disk 46 fixed on a shaft 47. Thus the sprocket roller 40 receives a quarter revolution for each revolution of the shaft 47. Fixed on the shaft 47 is a pinion 48 meshing 85 with a gear 49, and shaft 49¹ carrying pinion 49², meshing with gear 17 upon the shaft 18.

Mounted upon the machine frame by means of a suitable bracket 50 is an arm 51, 90 terminating in a sleeve 52. Said sleeve is carried upon a supporting shaft 53, mounted in the bracket 50. On the sleeve 52 is a two-faced block or cam 54 against which presses a leaf-spring 55. On the supporting shaft 95 53 is also carried a short arm 56 having a sleeve 57 embracing said shaft 53. A spring 58 is coiled about said sleeves upon the shaft 53, and has its ends bent so that one end bears on one side of the arm 51 and the other 100 end bears upon the opposite side of the arm 56. The arm 56 is provided with a finger piece 60 preferably integral with the sleeve 52. Carried upon the arm 56 is a supporting shaft 61, upon which is carried a roller 62. 105 Said roller has at either end thereof an annularly grooved part, each of which parts is adapted to bear against the corresponding part of the roller 40, and to press the film strip thereagainst just at either side of the 110 sprocket holes and sprocket teeth.

In the embodied form of continuously running rewinding means, a sprocket roller 64 is mounted upon a shaft 65 carried by the frame plate. Said sprocket roller has fixed 115 to turn therewith a belt pulley 66. Suitably supported upon a bracket 67 is a rewinding reel 68 carried upon a shaft 69, which shaft 69 may have a suitable locking latch 70. Frictionally engaging the reel 68 is a belt 120 pulley 71. A belt 72 runs over the pulleys 66 and 71, being arranged for slipping to compensate for the variations in the size of the film strip roll upon the reel 68. A suitable guiding roller 73 serves to keep the film 125 strip in position over the sprocket roll 64. Mounted in the end of the arm 51 upon a suitable supporting shaft is a roller 74, having annularly grooved end portions 75 adapted to hold the film strip against the 130

sprocket roller 64 at either side of the sprocket teeth, as will clearly be seen from Fig. 4. Fixed upon the arm 51 is a pin 76, and fixed upon the arm 56 is a finger or 5 face 77.

In threading the film strip through the machine, the arm 51 is bent backwardly as shown in Fig. 1, and the film is led downwardly over roller 62, around roller 74, over 10 sprocket wheel 64, and under guide roller 73, and attached to the reel 68. As the arm 51 is drawn backwardly, the pin 76 contacting with the face 77, draws backwardly also the arm 56 and the roller 62. The leaf spring 15 55 coöperating with the faces 54 acts to hold the arm 51 in either position. After the film is threaded through, the arm 51 is moved inwardly until its roller 74 bears upon the continuously running sprocket roller 64 20 as shown in Fig. 2. An adjusting or regulating stop may be provided for the arm 51 generally similar to the stop 30 of the arm 21. When the arm 51 is moved to the position shown in Fig. 2, it will be seen that a 25 reserve loop of precisely the desired length has been established between the intermittently feeding sprocket roller 40 and the continuously running sprocket roller 64, the arm 51 in its other position having served as 30 a measure for said loop.

Means are provided for adjusting the film strip relatively to the aperture 31 in the frame plate 4 at the back of the projecting lens tube 3, to properly "frame" the picture 35 in the machine, said means being operable without disturbing the threading of the film strip over the sprocket roller. In the embodied form thereof, the shaft 43 of the intermittent sprocket roller 40 is mounted in 40 a bearing 80. Said bearing 80 is carried by a sleeve 81, which in turn is mounted upon an inner sleeve 82 about the shaft 47, said sleeve 82 being formed on the frame 2. Fixed to said sleeve 81 is an arm 81¹, having 45 thereon a pivotally mounted lug 83. Said lug 83 is internally threaded to receive the threaded end of a rod 84, which rod 84 passes through an aperture in a boss 85 upon the machine frame. Said rod 84 terminates 50 in a knurled head 86. A compression spring 87 is conveniently coiled about the rod 84 between the lug 83 and the boss 85. If desired, pins 88 and 89 may be utilized to limit the amount of movement of the arm 81¹.

55 The film strip is adjusted relatively to the opening 31 by turning the knurled head 86 of the rod 84. This causes the rotatable lug 83 to travel along said rod, and by reason of the pivotal mounting of the sleeve 81 upon the sleeve 82, the intermittent sprocket roller 40 is moved either upwardly or downwardly as indicated by the full and dotted line positions in Fig. 5 and the film strip is thus moved with respect to the opening 31. 60

65 By reason of the action of the spring 58,

the roller 62 will follow the intermittent sprocket roller 40 and yieldingly press thereagainst in any adjusted position.

Suitable driving connections for the various parts, in addition to those already described will be provided, and much thereof is shown at the left of Fig. 3, but need not be described therein in detail.

70 From all the foregoing it will be understood that mechanisms and devices have been provided realizing the objects and advantages enumerated, together with other objects and advantages, and it will be further understood that changes may be made from the precise mechanism shown 75 and described, within the scope of the accompanying claims, without departing from the principles of the invention and without sacrificing its chief objects and advantages.

80 I claim:

85 1. A moving picture apparatus including in combination picture projecting means, a continuously driven sprocket for supplying a film strip, means for intermittently feeding the film strip past the picture projecting means, an arm carrying two rollers, said arm being swung into one position during the threading of the film strip through the machine to determine and establish a reserve loop of film between said continuously 90 driven sprocket and said intermittent feeding means, said arm being also movable into position when the film strip is running so that said rollers act as guiding and bearing rollers for the film strip.

100 2. In a motion picture machine, a film engaging member mounted in the machine relative to the film path and adapted to be controlled so as to be moved positively into either one of two positions, said member in 105 one of its positions engaging the film as a presser roller and in the other position adapted to have the film passed about it thereby to form a loop in the film.

110 3. A motion picture machine including in combination picture projecting means, means for intermittently feeding the film past the projecting means, means for supplying film thereto, and a member mounted in the machine between the film supply 115 and the intermittent feeding means and adapted to be controlled so as to be moved positively into either one of two positions, said member in one of its positions engaging the film as a presser roller and in the other position adapted to have the film passed about it thereby to form a loop in the film.

120 4. A motion picture machine including in combination projecting means, an intermittently rotating sprocket wheel engaging the 125 film to feed it past the projecting means, film rewinding means comprising a continuously rotating sprocket wheel, a roller carrier, a roller mounted thereon and pressing the film against the intermittently rotating 130

sprocket roller, a second roll carrier, a roller mounted thereon and pressing against the continuously rotating sprocket, the rollers and carriers being movable away from their sprockets to permit the threading through of the film and to establish a reserve loop in the film.

5. A motion picture machine including in combination picture projecting means, film handling devices at each side of the projecting means, said devices each including a swinging carrier, movable into film feed-

ing and film threading positions, and having two rollers mounted on each carrier serving to establish the length of film loop 15 when in threading position and to guide the film when in feeding position.

In testimony whereof I have signed my name to this specification in the presence of two subscribing witnesses.

JOHN DARBY.
